UNITED STATES PATENT OFFICE.

THOMAS B. WREN, OF MAHANOY CITY, PENNSYLVANIA.

HACKSAW AND FRAME THEREFOR.

1,206,638.

Specification of Letters Patent. Patented Nov. 28, 1916.

Application filed October 28, 1914. Serial No. 869,122.

To all whom it may concern:

Be it known that I, THOMAS B. WREN, a citizen of the United States of America, residing at Mahanoy City, in the county of Schuylkill and State of Pennsylvania, have invented a new and useful Hacksaw and Frame Therefor; and I do hereby declare the following to be a full, clear, and exact description of the invention, such as will enable others skilled in the art to which it appertains to make and use the same.

This invention relates to a new and useful hack saw and adjustable frame therefor.

An object of the invention is the provision of a frame for a hack saw which may not only be adjusted lengthwise, but laterally as well.

Another object of the invention is the provision of means whereby the hack saw blade may be adjusted annually upon its axis, and held in a positive adjustable position.

One of the features of the invention is the strap loops for holding the adjustable parts of the frame alined, said loops being removable.

In practical fields the details of construction may be subjected to alterations, falling within the scope of what is claimed.

20 The invention comprises further features and combination of parts, as hereinafter set forth, shown in the drawings and claimed.

In the drawings, Figure 1 is a view in perspective of the improved hack saw and frame constructed in accordance with the invention. Fig. 2 is a sectional view on line 2—2 of Fig. 1, showing the adjustable connections for the blade. Fig. 3 is a sectional view on line 3—3 of Fig. 1, showing the adjustable connections for adjusting the frame lengthwise. Fig. 4 is a sectional view on line 4—4 of Fig. 1 showing the adjustable connections of the frame whereby it may be adjusted laterally or at right angles 45 to the lengthwise adjustment.

Referring more particularly to the drawings, 1 designates the frame, which comprises four sections, two angular sections 3 and 4, the parts 5 of which are arranged 50 parallel to one another and held in such wise by the straps 6 and 7. The strap 6 is provided with an aperture 8 to receive one of the lugs 9 of one of the parts 5 to hold the strap against displacement. The 55 strap 7 is provided with a thumb screw 10, not only passing through the strap, but also

through one end of one of the parts 5, so as to engage any one of the depressions 11 of the opposite part 5. However, the thumb screw of the strap 7 may also be threaded 60 to the aperture 13 of the part 5 carrying the strap 7. Each end of the arm 14 of each of the sections 3 and 4 is provided with a lug 15 passing through an aperture 16 of the strap 17. These straps 17 also receive 65 the third and fourth sections 18 and 19 of the frame. The straps 20 also hold the arms 14 and the third and fourth sections 18 and 19 of the frame together, there being thumb screws 20^a passing through the straps 20 70 and through the sections 18 and 19 so as to engage the depressions 21 of the arms 14, whereby the sections 18 and 19 and the arms 14 may be held in adjusted positions relative to one another.

75 The ends 22 of the sections 18 and 19 are provided with sleeves 24 and 25 having ears 26 riveted to the sections 18 and 19. The sleeve 24 is provided with a plug 27, one end of which is provided with a transverse 80 pin 28, the ends of which are received in any two opposite notches 24^a of the sleeve to hold the plug in adjusted positions, there being a pin 29 to hold the plug against being removed. The plug is constructed with 85 a recess 30 having an angularly disposed stud 31 to enter an aperture of the saw blade. The end wall of the recess 30 overhangs the end of the blade, as shown, thereby necessitating the blade being disposed at 90 an angle to the plug in connection with the same. The sleeve 25 is likewise constructed with notches 32, any two opposite notches being designed to receive the two projections 33^a of the plate 33, which has a lug 95 and slot connection 34 with the screw plug 35, on which the handle 36 is threaded, which handle screws against the plate 33 to hold the bulges in said notches, there being a lock nut on the screw plug to hold 100 the screw plug in adjusted positions, the lock nut being designated by the numeral 37. The other end of the saw blade is connected to a lug 38 of the screw plug. By loosening the lock nut the handle may be 105 unscrewed thereby loosening the screw plug whereby the blade may be disconnected or connected. After the blade is connected as shown in Fig. 1 the handle may be screwed tight against the plate 33 so as to hold the 110 blade firm, while the notches of both of the sleeves prevent the blade from twisting.

It will be observed that by the provision of the notches, the blade may be held with its flat surface in a plane parallel with the plane of the frame, or at right angles to the plane of the frame, or at intermediate angles, such as forty-five degrees, to one side or the other.

In a number of instances, in using a hack saw it has been found necessary to adjust 10 the blade with one hand, while holding that which is being operated upon with the other hand, and heretofore this could not be accomplished, owing to the fact that after adjusting one end of the blade and holding 15 the same in such position, it would necessitate the other hand, in adjusting the opposite ends of the blade, in which case the operator would have to leave go with the other hand that which is to be sawed or cut. However, in the present case the operator may 20 unscrew the handle, after which the spring 24^a, which is arranged between the pin 28 and the shoulder 24^b of the sleeve 24, will force the plug 27 forwardly carrying the 25 saw blade with it and also maintaining the blade substantially rigid between the two plugs 35 and 27. In moving the plug 27 forwardly the pin 28 is freed from said notches 24^a. Then by partially rotating the 30 plate 33 the two plugs and the blade may be simultaneously partially rotated or adjusted

with the one hand, while holding that which is to be cut or sawed with the other hand.

The invention having been set forth, what is claimed as new and useful is:—

In improvements in a hack saw construction, a frame, a saw blade, sleeves mounted on the inner and outer ends of the frame and having corresponding notches in their outer edges, plugs loosely mounted in the 40 said sleeves, one connected to each end of the saw blade, a handle threaded on one of the plugs and having means co-operating with the adjacent sleeve whereby the plug may be adjusted longitudinally upon its 45 axis, said means having projections to engage the notches in the edge of the inner sleeve, the plug of the outer sleeve having a transverse pin for engagement with the notches of the outer sleeve, and a spring in 50 said outer sleeve interposed between one end of said outer sleeve and the pin for holding the saw blade taut while it is being adjusted on its axis.

In testimony whereof I have signed my 55 name to this specification in the presence of two subscribing witnesses.

THOMAS B. WREN.
